HINGE-HOLDING MECHANISM

Paul H. Durup, Wollaston, Mass., assignor to
Joseph D. Ramsey, Watertown, Mass.

Application October 7, 1947, Serial No. 778,389

1 Claim. (Cl. 16—142)

1

This invention relates to hinges and more especially to a combination hinge and catch for doors, covers, gates and various other structures which are required to be pivotally secured.

An object of the invention is to improve hinges and to devise a catch mechanism which, in response to movement of one section of a hinge member, is capable of detachably securing the door or other structure referred to in closed position. Another object of the invention is to devise a catch mechanism which may be constructed as an integral part of a conventional hinge and thus eliminate the use of separate latching mechanisms or other fastening means. Still another object of the invention is to provide a simple, cheap and easily installed hinge and catch arrangement which is easily engaged and disengaged and which is completely concealed from view when in a closed condition. These and other novel features will appear from the following description of the invention.

In the accompanying drawings:

Fig. 1 is a fragmentary perspective view of a door supported in a door jamb by means of hinges made in accordance with the invention;

Fig. 2 is a plan view showing a single hinge in a fully opened position;

Fig. 3 is an end elevational view of the hinge in an open position;

Fig. 4 is a cross-sectional view further illustrating a door in a closed position and being temporarily fastened by the hinge of the invention;

Fig. 5 is a detail elevational view illustrating a modified retaining element;

Fig. 6 is a fragmentary perspective view illustrating another form of catch mechanism for a hinge;

Fig. 7 is a plan view of the catch mechanism shown in Fig. 6;

Fig. 8 is an end elevational view of the hinge shown in Fig. 6;

Fig. 9 is a cross sectional view of the same; and

Figs. 10 and 11 illustrate slightly modified forms of the structure shown in Figs. 6-9 inclusive.

The improved hinge and catch mechanism has been illustrated in the drawings for use in supporting a door in a door jamb, and this arrangement is intended to be generally illustrative of application of the hinge to various types of pivoted members such as a cabinet door, covers for containers of varying types, gates, and numerous other structures where a pivoted arrangement is desirable. In making the combination hinge and catch shown in the drawings, various types of materials may be resorted to, including metals,

plastics, and the like, with a conventional hinge material such as brass or a chrome alloy being found most desirable.

A preferred embodiment of the invention includes a pair of hinge sections pivotally secured one to the other, each of which carries one element of a catch mechanism adapted to be brought into interlocking relation when the hinge sections are swung into a closed position. One desirable form of the invention is illustrated in Fig. 1, comprising a door 12, supported by a plurality of hinges, of which hinge sections 14 are fastened to an edge of the door by means of screws 16 and hinge sections 18 are pivotally mounted on fixed hinge sections 18, in turn fastened to a door jamb 20 by screws 22. The two sections 14 and 18 of each hinge are interchangeable in respect to the manner of attachment to the door and door jamb described.

20 In securing the hinges in place the hinge section 14 is preferably set into a recess 26 cut in the edge of door 12 so that the upper face of section 14 lies in a plane slightly below the surface 24 of the door 12. The depth of recess 26 25 may for example conveniently consist of a distance equal to one-half of the thickness of the hinge section 14. Similarly, the hinge section 18 is set into a recess 28 in door jamb 20 to approximately the same depth.

30 At the central portion of hinge section 18, there is formed a socket comprising a split ring 32 and a series of annularly spaced-apart fingers 30 which are struck from the material of which the hinge section 18 is comprised, for example by means of a die. The fingers 30 have their upper extremities rounded over a position to loosely retain the split ring member 32 which is preferably formed of resilient material such as spring steel. In this position the split ring may be expanded into a slightly greater circumference while still enclosed by the fingers.

40 Mounted for engagement with the expanding ring member 32 is a button-shaped projection 34 extending upwardly from the central portion 45 of the hinge section 14. The projection 34 consists of a flattened head whose circumference is slightly greater than the circumference of the split ring in its normally closed position, and the flattened head is supported by a reduced neck 36. 50 Preferably the projection 34 is formed integral with the hinge section by dieing out an extruded projection 40 as shown in Fig. 5.

55 In actual use of a door equipped with my improved combination hinge and catch, the door 12, for example, is swung from a position such

as that indicated in Fig. 1 into a fully closed position as indicated in Fig. 4, with the hinge section 14 moving into position with the hinge section 18 as shown. As this movement takes place, the flattened head of projection 34 becomes forced through the split ring which expands to permit passage of the flattened head and then contracts to bear lightly against the reduced neck 36. This provides a light yet positive holding means for maintaining the hinge sections and door in a closed position and thus serve the purpose of an outside door latch or other locking mechanism and yet at the same time remains entirely concealed from view. In opening the door 12, no separate unlatching operation is necessary as a light pull on the door, applied through a knob or other suitable handle at the outside thereof, will readily disengage the projection 34 from the split ring 32, thus permitting the door to be swung outwardly. By suitably adjusting the tension of the split ring 32, it is possible to control the holding action of the hinge so that while it is readily opened as noted above, it nevertheless eliminates any tendency for the door to rattle or squeak when in a closed position and acted on by drafts or other agencies.

Another desirable embodiment of the invention may consist of a catch mechanism such as that shown in Figs. 6-9 inclusive, in which two hinge sections 42 and 44, secured in a recessed manner, as described above, are formed with up-set lug portions 46 and 48. The latter elements are reversely bent to form interlocking surfaces which may be brought together in the manner indicated in Fig. 9, and thus function to detachably hold the hinge sections in a suitably closed position. In forming the reversely bent lugs 46 and 48, there are preferably provided extended slots 50, 51, 52 and 53 in the hinge section material, and these slots may conveniently be formed in the same dieing operation which forms the lugs. The purpose of the slots is to impart a greater degree of springiness to the upstanding lugs so that they tend more readily to flex into and out of interlocking engagement with one another when the hinge sections are brought together. The lug construction described may also conveniently take the form illustrated in Figs. 10 and 11, in which the lugs 54 and 56 are located along the edges of the constituent hinge sections. This arrangement is especially suited to application with very small and especially narrow hinge sections. With these narrow hinge sections, it may also be found desirable to extend the slots transversely as is illustrated by the slots 58 in Fig. 10. Similarly the lugs may take other forms and be located at other points along the hinge surfaces.

It will be found from the foregoing description of the invention, that I have provided a simple, cheap and efficient catch mechanism combined with a hinge to aid in closing and fastening various types of doors, covers, gates and other pivotally supported structures. It should also be understood that the invention is not limited to

the particular form of hinge noted but is suitable for use wherever two opposing surfaces are moved into close proximity to one another during the opening or closing of one of the structures referred to. For example in some types of hinge arrangements, the two hinge sections may contact one another and in this case it may be desired to provide for one of the catch elements projecting through a hinge section into the wood or other supporting surface to which the hinge section is fastened. In this case the wood could be cut away to permit such entry by the catch element. I may also desire to adapt the catch mechanism to a hinge construction in which one hinge section approaches or comes into contact with the inner edge of the pivoted member. In this type of hinge, I may apply one catch element directly to the edge of the pivoted member and the other catch element may be mounted on a hinge section in the manner already described and in a position to engage with the first catch element.

It will be evident that the use of the combination hinge and catch is extremely convenient and eliminates the need of separate latch or locking mechanisms as well as the cost of these items and their installation. It should also be observed that by combining the catch mechanism directly in the hinge sections, there is less likelihood of doors and covers getting out of adjustment such as sometimes happens when a door or cover sags in its jamb, thus throwing out of alignment a catch element fastened to the outside of the door relative to a catch element located on the door jamb. The arrangement of the catch mechanism at the hinge point results in this catch mechanism being substantially independent of possible sagging and thus rendering satisfactory service over long periods of time.

I claim:

40 An improved hinge comprising two hinge sections pivotally secured together about a common axis of rotation, means for locking the hinge sections in a closed position, said means including a pair of interengaging elements, one of said elements being a headed projection carried by one of said hinge sections, and the other element a socket to receive said headed projection, said socket comprising a split spring ring and a series of fingers struck from the other hinge section, which fingers engage spaced outer portions of said ring.
